(57) **CLAIM**

The ornamental design for a toolbox on wheels, as shown and described.

DESCRIPTION

FIG. 1 is a perspective view of the top side my new design. FIG. 2 is a perspective view of the bottom side thereof.

FIG. 3 is a front side plan view thereof.

FIG. 4 is a back side plan view thereof.

FIG. 5 is a right side plan view thereof.

FIG. 6 is a left side plan view thereof.

FIG. 7 is a top side plan view thereof; and,

FIG. 8 is a bottom side plan view thereof.

The broken lines illustrate portions of the toolbox on wheels and form no part of the design claimed.
